[57] CLAIM

The ornamental design for a “toy top with launching handle”, as shown and described.

DESCRIPTION

FIG. 1 is a side left side elevational view of a toy top with launching handle showing our new design, the right side being a mirror image;

FIG. 2 is a top plan view thereof;

FIG. 3 is a bottom plan view thereof;

FIG. 4 is a rear elevational view thereof;

FIG. 5 is a front plan view thereof;

FIG. 6 is a front elevational view of the top, shown separately for clarity of illustration, the rear and sides being identical;

FIG. 7 is a top plan view of FIG. 6;

FIG. 8 is a bottom plan view of FIG. 8;

FIG. 9 is a top plan view of the launching handle, shown separately for clarity of illustration;

FIG. 10 is a left side elevational view of FIG. 9, the right side being a mirror image;

FIG. 11 is a rear elevational view of FIG. 9; and,

FIG. 12 is a front elevational view of FIG. 9.

A propelling string not shown, which winds around the stem of the toy top in FIG. 6 and exits through the right or left slots on the launching handle seen in FIG. 9, forms no part of the claimed design.
